GUITAR STEEL

Francis William Wright, Coshocton, Ohio

Application March 30, 1948, Serial No. 18,029

3 Claims. (Cl. 84—319)

1

This invention relates to improvements in guitar steels for stopping the strings of guitars and similar musical instruments in a manner to give certain qualities to the strings, and the primary object of the invention is to provide a more efficient, more easily manipulatable, and more comfortable device of this kind, which can be produced of highest grade material at relatively low cost.

Other important objects and advantageous features of the invention will be apparent from the following description and accompanying drawings, wherein for purposes of illustration, a specific embodiment of the invention is set forth in detail.

In the drawing:

Figure 1 is a side elevation, partly broken away, showing the illustrated device in position on a guitar player's finger.

Figure 2 is a fragmentary top plan view of Figure 1.

Figure 3 is a left-hand end elevation of the device, with the retaining spring removed.

Referring to the drawings in detail, the device shown comprises a body 5 preferably of 20-gage stainless steel, of semi-circular cross-section, to receive the finger 6 of a guitar player lengthwise, the rear end of the body being open and the forward end closed by a semi-circular segmental portion 8, conforming to the rounded finger tip 9.

For securing the body 5 in place on the player's finger 6, outturned tabs or lugs 10, 10 are provided on the opposite side edges 11, 11 of the body at a point about one-third the length of the body from its rear end 7, with which are engaged the terminals 12, 12 of a flat expanding spring 14, on the order of that embodied in expansible watch bands, likewise of stainless steel, and stretched tightly enough to exert sufficient pressure upon the back of the player's finger 6 to hold the body 5 engaged with the underpart of the finger 6 and to preclude endwise movement of said body relative to the finger in ordinary service.

The body 5 with its spring retaining lugs 10, 10 can be produced by a single stamping operation from a single blank of material, and different sizes can be provided if desired, all at very little cost for materials and manufacture.

What is claimed is:

1. A guitar steel comprising a sheet metal body of semi-circular cross-section elongated to conformably receive a major portion of the underside of a player's finger, the rear end of said body being open and the forward end of said body

2

being closed by a semi-circular segmental portion to conformably receive the tip of the player's finger, and contractile means extending across said body between the side edges thereof to overlie the back of the player's finger in a manner to retain the said body engaged with the underside of the player's finger and preclude forward endwise movement of said body relative to the player's finger.

10 2. A guitar steel comprising a sheet metal body of semi-circular cross-section elongated to conformably receive a major portion of the underside of a player's finger, the rear end of said body being open and the forward end of said body in detail.

15 15 being closed by a semi-circular segmental portion to conformably receive the tip of the player's finger, and contractile means extending across said body between the side edges thereof to overlie the back of the player's finger in a manner to retain the said body engaged with the underside of the player's finger and preclude forward endwise movement of said body relative to the player's finger, said contractile means comprising a flat expanding spring stretched across the side edges of said body and having its ends secured to the latter.

25 3. A guitar steel comprising a sheet metal body of semi-circular cross-section elongated to conformably receive a major portion of the underside of a player's finger, the rear end of said body being open and the forward end of said body in detail.

30 30 being closed by a semi-circular segmental portion to conformably receive the tip of the player's finger, the side edges of said body being straight for substantially their entire length and parallel to the bottom of said body, a lug on each of the side edges of said body, and contractile means embodying a flat expanding spring stretched between said lugs and secured at its ends to the latter to overlie the back of the player's finger in a manner to retain the said body engaged with the underside of the player's finger and preclude forward endwise movement of said body relative to the player's finger.
